UNITED STATES PATENT OFFICE.

MICHEAL E. HERBERT, OF ST. JOSEPH, MISSOURI.

STEAM-BOILER.

SPECIFICATION forming part of Letters Patent No. 310,423, dated January 6, 1885.

Application filed July 18, 1884. (No model.)

To all whom it may concern:

Be it known that I, MICHEAL E. HERBERT, of St. Joseph, in the county of Buchanan and State of Missouri, have invented a new and useful Improvement in Steam-Boilers, of which the following is a full, clear, and exact description, reference being had to the annexed drawings, forming part thereof.

My invention is an improvement in the class of steam-boilers formed of two horizontal sections, which are of semi-annular or approximately semi-annular shape, and have connecting-pipes, and are so separated and arranged as to form between them a flue; through which the products of combustion pass to the stack or chimney.

My improvement is embodied in the specific construction, arrangement, and combination of parts hereinafter described and claimed.

20 In the drawings, Figure 1 is a longitudinal section of my invention in perspective, and Fig. 2 is a perspective view of the boiler detached from the masonry.

A indicates the inner and lower section, and 25 B the upper and outer section, of the boiler. The two sections are made semi-annular in cross-section, and the upper section is made of greater capacity at its middle or higher portion to provide space for the steam. The 30 two sections are connected together by the circulating-pipes C at the front end, which connect the top portion of the lower section with the end of the upper section, and by the pipes D at the sides, which connect the lower 35 portion of one section with the lower portion

of the other. The rear end of the upper section at E is made semi-cylindrical to form a wall for closing the rear end of the furnace, and to utilize the heating-surface thus provided. The inner section is arranged to leave 40 a space between its rear end and the rear wall of the upper section, to provide a continuous passage or flue from the combustion-chamber along between the said sections to the front of the boiler. The brick-work F forms a continuation of the flue back over and along the upper section to the chimney G.

H indicates the coal-magazine, located at the front end of the upper section, and partially set within the lower section, and having 50 its lower end slightly inclined to the rear. The bridge I is made hollow, and communicates with the sides of the lower section, forming a part thereof.

What I claim is—

55 The combination of the upper section, having a semi-annular chamber communicating with a semi-cylindrical chamber at its rear end, the lower and inner section having a semi-annular chamber, and having the hollow 60 bridge communicating therewith, the circulating-pipes connecting said sections together, and the coal-magazine located at the front end of the boiler, substantially as shown and described.

MICHEAL E. HERBERT.
